UNITED STATES PATENT OFFICE.

RUDOLF KLEIN, OF SPOKANE, WASHINGTON.

DESIGN FOR A CUP.

56,749.

Specification for Design.

Patented Dec. 14, 1920.

Application filed July 29, 1920. Serial No. 399,909. Term of patent 14 years.

To all whom it may concern:

Be it known that I, RUDOLF KLEIN, a citizen of the United States, residing at Spokane, in the county of Spokane, State of Washington, have invented a new, original, and ornamental Design for a Cup, of which the following is a specification, reference being had to the accompanying drawing, in which—

I claim:—

The ornamental design for a cup as shown. In testimony whereof I affix my signature.

RUDOLF KLEIN.
